ATTORNEY

UNITED STATES PATENT OFFICE

LOUIS BERNIER, OF FERNDALE, MICHIGAN

AUTOMATIC SWITCH CONTROL

Application filed February 11, 1929. Serial No. 338,994.

My invention relates to a new and useful improvement in an automatic switch control adapted for use on railroad tracks, the present invention being an improvement on my 5 invention set forth in my application for United States Letters Patent, Serial Number 268,570, filed April 9, 1928.

The invention is used with a device whereby mechanical means are provided so that 10 the operator of a vehicle traveling over tracks may automatically, without leaving the vehicle, and while the vehicle is still traveling, operate the switch.

The construction set out in the application referred to is such that the operating mechanism after being operated to throw the switch in one direction is automatically set for throwing the switch in the opposite direction and will function efficiently for this purpose. 15 However, should the switch be thrown without actuating the automatic switch operating mechanism this operating mechanism would then be in a position other than the desired position for operating the switch and it is an 20 object of the present invention to obviate such a situation.

It is another object of the invention to provide yieldable means for maintaining the rockable actuating finger in proper operating 25 position at all times regardless of whether the switch has been thrown by the actuating mechanism or moved in some other manner.

Other objects will appear hereinafter.

The invention consists in the combination 30 and arrangement of parts hereinafter described and claimed.

The invention will be best understood from a reference to the accompanying drawings which form a part of this specification, and 35 in which,

Fig. 1 is a top plan view of the invention showing it installed.

Fig. 2 is a sectional view taken on line 2—2 of Fig. 1, with a fragment of a vehicle shown 45 thereon.

Fig. 3 is a perspective view of the operating mechanism used in the invention.

Fig. 4 is a sectional view taken on line 4—4 of Fig. 3.

50 The device may be used on railroad tracks

extending beyond the limits of a city or may be used on street car tracks laid in the streets of a city, and in the drawings, I have illustrated the adaptation of the invention to the rails 9 and 10 which are laid in a street. A 55 branch track 11 is illustrated, in connection with which is used the swingably mounted rail or switch 12, the location of which will determine the direction of travel of a vehicle after passing the same when travelling from left to right on the drawings. Mounted between the rails 9 and 10 is a housing 13 having the cover 14 provided with a slot 15. Formed in this housing is a compartment 16 having the elongated portion 17, which extends beyond the free end of the switch rail 12. Mounted on the base 18 of this housing are spaced supports 19 and 20, extending slidably through which are the rods 21 and 22. Fixedly mounted on the rods 21 and 22 is the 60 bridge 23. Swingably mounted on the upper surface of the bridge 23 is the wedge-shaped actuating finger 24 carrying the wedge-shaped head 25 preferably formed integral therewith. Projecting upwardly from opposite sides of the bridge 23 are the studs or engagement members 26 and 27 which are adapted to engage opposite faces of the actuating finger 24, when the same is swung on its pivot. Preferably formed integral with and 65 projecting upwardly from the bridge 23 are the spaced lugs 28 and 29, between which engages one end of the rod 30 which is pivotally mounted on these lugs 29 and 28 and which passes between the supports 20. 70 Pivotally connected at one end to the outer end of the rod 30 is the operating bar 32 which is pivotally connected, intermediate its ends, at a flattened portion 33 to a support 34 positioned in the compartment 17. Connected 75 pivotally at one end to the opposite end of the bar 32 is a link 35 which is pivotally connected, intermediate its ends, to a pair of spaced lugs 36 and 37 which project outwardly from and are secured to one face of the 80 switch rail 12. Mounted on the undersurface of the floor 85 of the vehicle is a bolster 39. A rod 40 is projected through the floor 38 and through the bolster 39 so as to lie, when the vehicle is 90 100

drawn over the tracks, in alignment with the slot 15. A spring 41 serves to normally retain the lower end of the rod 40 spaced above the cover 14.

5 In operation, when the vehicle is being propelled over the rails 9 and 10 and the switch is approached, and it is desired to throw the switch to its other position, the operator of the vehicle will, by pressing on the head 42 of the rod 40, force the rod 40 downwardly against the compression of the spring 41 so that the lower end of the rod will engage in the slot 15, a collar 43 being fixedly mounted on this rod to engage the bolster 39 and limit the downward movement thereof. When the end of the rod 40 is in engagement with the slot 15 and the vehicle is drawn past the operating mechanism so as to cross over the location of the bridge 23, the lower end of the rod 40 will engage one face of the finger 24. As shown in Fig. 3, this finger is in engagement with the stud 27, and in order to permit the rod 40 to pass beyond the same, the rod engaging the inclined face of the finger will force the bridge to move toward the left, thus rocking the bar 32 and moving it into the position shown in dotted lines in Fig. 1, thus effecting a movement of the switch rails 12 into the position shown in dotted lines in Fig. 1. In this manner the switch is thrown. As the end of the slot 15 is approached, the end of the rod 40 will engage the inclined surface of the cover 14 at the end of the slot 15 so that it will move out of engagement with the slot 15 without striking any abrupt shoulder on the cover 14.

40 As the pin passes the wedge-shaped head 25, the finger 24 will be rocked on its pivot into the position shown in dotted lines in Fig. 1 so that the finger 24 will be moved into engagement with the stud 26. In this position a succeeding vehicle desiring to travel in the same direction as the preceding vehicle would not effect any operation of the switch, but one desiring to travel in a direction determined by the throwing of the switch into the position shown in full lines in Fig. 1 would press the rod 40 downwardly so as to operate the switch. The opposite face of the finger 24 would in this case be engaged and an opposite movement of the bridge 23 effected with a resultant rocking of the actuating finger 24 on its pivot to prepare it for the next operation, so that the switch may again be thrown into its prior position.

45 Mounted in fixed position forwardly of the supports 19 and 20 is a U-shaped member 44 projecting through the legs 45 and 46 of which are bolts 47 and 48, each having an eyelet 47' and 48' respectively. Projected through these eyelets are leaf springs 49 and 50 which project into slots 51 formed in a supporting member 52 carried by the U-

shaped member 44. A set screw 53 serves to bind the end of the leaf spring in the support 52. Formed in the bridge 23 is an arcuate slot 51' in which engages a pin 52' projecting downwardly from the actuating finger 24. Should the switch rail 12 for any reason be swung on its pivot without rocking the actuating finger 24, the saddle 23 would be moved longitudinally of the rods 21 and 22 by the pin 52 engaging in the position shown in Fig. 75 3, the leaf spring 50 and would cause the actuating finger 24 to be rocked so that it would be set in proper position for actuation and operation of the switch upon a vehicle passing thereover. Similarly, should the switch be thrown when the saddle 23 is in a position other than shown in Fig. 3, the engagement of the pin 52 with the spring 49 would again effect a rocking of the actuating finger 24, thus assuring the location 85 or positioning of this actuating finger 24 in proper position for operation by the rod 40 of a vehicle passing thereover.

90 In this way there is an additional safety feature provided for the switch actuating mechanism and there is provided means for maintaining at all times the actuating finger 24 in operative position.

95 While I have illustrated and described the preferred form of my invention, I do not wish to limit myself to the precise detail of structure shown but desire to avail myself of such variations and modifications as come within the scope of the appended claims.

100 Having thus described my invention, what I claim as new and desire to secure by Letters Patent is:

1. In a switch control of the class described adapted for use on a track having a movable switch rail: a bridge slidable transversely of said track; a rockable member on said bridge operative upon actuation when moved to one position for moving said switch rail in one direction and when moved in the other position for moving said switch rail in the opposite direction; and means for rocking said rockable member from one position to the other upon movement of said bridge transversely of said track through the movement of said switch rail. 110 115

2. In a switch control of the class described adapted for use on a track having a movable switch rail: a bridge movable transversely of said track; means for connecting said bridge to said switch rail for effecting movement of said switch rail simultaneously upon transverse movement of said bridge; a rockable member mounted on said bridge and rockable thereon and operable upon actuation, when in one position, for moving said bridge transversely in one direction and, when in the other position, for moving said bridge transversely in the opposite direction, said bridge having an arcuate slot formed therein; a pin mounted in said rockable man- 120 125 130

ner and projected downwardly through said slot; and resilient engagement means for engaging said pin and rocking said rockable member to normal position upon movement of said bridge transversely through a

5 movement of said rail.

In testimony whereof I have signed the foregoing specification.

LOUIS BERNIER.
